UNITED STATES PATENT OFFICE.

ISAAC E. PALMER, OF MIDDLETOWN, CONNECTICUT.

DESIGN FOR A HAMMOCK.

SPECIFICATION forming part of Design No. 21,434, dated March 29, 1892.

Application filed February 29, 1892. Serial No. 423,287. Term of patent 14 years.

To all whom it may concern:

Be it known that I, ISAAC E. PALMER, of Middletown, in the county of Middlesex, in the State of Connecticut, have invented and produced a new and original Design for Hammocks, of which the following is a specification, reference being had to the accompanying drawing, forming part thereof.

The leading features of my design are the longitudinal stripes along the opposite edges, the cross-stripes at the end, and the compara-

tively open or plain center surrounded by the stripes. The center is designated by A, the side stripes by B *b*, and the end or cross-stripes by C *c*.

What I claim is—

The design for a hammock, as herein shown and described.

ISAAC E. PALMER.
